UNITED STATES PATENT OFFICE.

ARTHUR F. PYM, OF LYNN, MASSACHUSETTS, ASSIGNOR TO UNITED SHOE MACHINERY CORPORATION, OF PATERSON, NEW JERSEY, A CORPORATION OF NEW JERSEY.

MANUFACTURE OF SHOES.

Application filed November 28, 1921. Serial No. 518,294.

This invention relates to the manufacture of turned shoes, and is directed particularly to improving the shape given such shoes during their manufacture, the present application being in part a continuation of my pending application Serial No. 443,043, filed February 7, 1921.

In the manufacture of shoes of this type as heretofore made, the three operations of 10 first lasting, second lasting, and treeing have all been relied upon as important factors in imparting to the shoes the desired shape. While in ordinary practice the second lasting is particularly important in the shaping 15 of turned shoes, nevertheless, in spite of efficient second lasting, there remains a good deal of final shaping to be done in the treeing operation. Too much reliance upon treeing, or any other operation involving stretching or shrinking of the leather, is undesirable, and an object of the present invention, 20 therefore, as hereinafter more fully set forth, is to minimize the shaping which must be effected by the treeing operation by improving the first lasting and second lasting operations.

It is usual to provide a smaller first than second last, to compensate roughly for the change caused by turning the shoe, but so far 30 as I am aware it has not previously been proposed to design a first last differently from the corresponding second last, to provide an exact compensation for this change. At present the first last is customarily just like 35 the second last except that it is one-half size shorter or narrower. Now the second last must necessarily be narrower than the sole of the shoe, since it is to go inside of the shoe after it is turned, and the first last is therefore, according to the present system, still 40 narrower. Thus the sole of the shoe, when placed thereon in the assembling operation, projects on all sides beyond the first last. Obviously it is difficult to last and stitch such 45 a shoe tightly on account of this unsupported margin, even if a first last could be used which affords an accurate form over which to shape the shoe. Moreover, even if, in a special case, the sole were stiff enough to support itself sufficiently to permit the accurate 50 and tight lasting which is usual, for example, with Goodyear welt shoes, since the

first last bears no definite relation to the second last other than being smaller by an arbitrary amount which is the same for large 55 as for small shoes, a shoe which was so conformed to the first last would not fit equally well over the corresponding second last.

With these difficulties in view, my invention, in one of its aspects, contemplates the 60 use of a first last differing from the corresponding second last in the shape and size of cross-sections through its various parts, in an amount exactly to compensate for the changes caused by turning a shoe lasted 65 thereon. It is preferred, further, that the first last be wider across the bottom of its forepart than the corresponding second last, so as to support an entire sole, clear out to its edges, in the manner of a welt insole, thus 70 providing for securing the same tight and efficient lasting with turned shoes as with Goodyear welts.

Having in mind the importance of improving the shaping of the shoe during the step 75 of relasting, as above explained, in a further aspect my invention contemplates a novel process of seating a second last in a shoe after turning which permits as tight a fit of the shoe on this last as if it were 80 still on a first last. While this is especially advantageous in manufacturing turned shoes according to the older methods; it is also well adapted to be used in connection with my improved first lasting operation 85 discussed above.

According to this novel process the shoe 90 is engaged in such a manner that as the shoe and last are relatively moved, the shoe upper is broadened, so that it may afterwards contract by reason of the elasticity of the leather into tight engagement with the last. It is also my intention to avoid any possible damage to the shoe when relasting it so tightly, 95 by permitting slippage to occur when the last has been seated in the shoe. I prefer to bring about both of these results by engaging the forward part of the shoe by a friction member, which can slip when the relasting operation is completed, and which acts by a pushing action to broaden the shoe upper as it is forced on a last. I prefer also to aid in smoothly seating the last in the shoe 100 by relatively tipping the last and shoe so

that the toe of the last does not catch on the channel lip of the sole, by relatively twisting the last and shoe to guide their relative longitudinal movement, by stretching and smoothing out the lining during the relasting, and by other related operations hereinafter described.

According to the grade of the shoe, and the consequent ease of manipulating it, I 10 may utilize the friction member progressively to force the shoe bottom against the last during the relasting of the counter portion of the shoe, or avoid possible "overshot" toes by using it to seat the last carefully in exactly 15 the correct position in the toe and then to hold the shoe and last tightly clamped together while the counter is relasted. Alternatively, if it is desired to avoid straining the back seam, I may move the toe of the 20 last further into the shoe than its final position, to provide additional clearance at the heel, and after the relasting of the counter move the shoe relatively to the last in a forward direction to take up the looseness introduced by providing such additional clearance.

It is also desirable to avoid any looseness in the upper by lacing or otherwise securing it about the second last while the shoe bottom is tightly compressed against the last; or the desired tight fit may be obtained by lacing the shoe and then forcing the instep block into place while the shoe bottom is under such pressure.

The above and other aspects of the invention including the form of the required apparatus, and the manner of operating it, will be apparent from the following description of the various figures in the accompanying drawings, in which:

Fig. 1 is a side elevation showing, in full lines, my improved first last and in dotted lines a corresponding second last;

Figs. 2 and 3 are respectively sections on the lines 2-2 and 3-3 of Fig. 1, showing sections of the lasts;

Figs. 4 to 10 are diagrammatic figures illustrating the successive steps of one manner of carrying out my novel process of relasting shoes;

Fig. 11 is a perspective view of a toe shoe horn used to stretch and smooth the lining during relasting;

Figs. 12 to 18 are a series of diagrammatic views corresponding to Figs. 4 to 10, and illustrating the successive steps of an alternative manner of carrying out my novel process of relasting shoes;

Fig. 19 is a view corresponding to Fig. 13 60 of my prior application Serial No. 443,043, filed Feb. 7, 1921, illustrating a modification of the apparatus shown and claimed in that application, to adapt it for use in performing the method of Figs. 12 to 18 (the apparatus as shown in the said application

being adapted for use in carrying out the method of Figs. 4 to 10 herein);

Fig. 20 is a cross-section of a preferred form of shoe-engaging roll for use in the apparatus of the above-identified prior application; and

Fig. 21 is a diagrammatic view illustrating the use of a fabric to enable the shoe-engaging roll to get a grip on soles which are moist and slippery by reason of being in temper, or to protect a finished surface from injury by such a roll.

In Figs. 1 to 3, my improved first last is shown in full lines, and the corresponding second last in dotted lines. As explained above, and as will be obvious from a comparison of the three figures, the first last has less material across the top of the forepart and the bottom of the rear part, as compared with a corresponding second last, in an amount just sufficient to compensate for the change of the inside of the shoe due to turning. Such change is due in part to the reversal of materials, such as the counter and the sole, which are inside the upper in one position and outside in the other position, and in part to the fact that on the first last the upper passes over the edge of the sole to reach the seam while on the second last it does not.

In connection with the latter fact, attention is called to Fig. 2, showing in broken lines a sole in position on the first last. The sole so shown is also, as will be seen, in correct position with respect to the second last except that it is upside down. In first lasting, the upper must reach from "a" around "b", "c", and "d", to "e"; whereas on the second last it does not pass over the edges "b" and "d" of the sole, but only through the distance A-C-D. Accordingly, an important aspect of my invention is in so relating the lasts that the distance a-b-c-d-e shall equal the distance A-C-D. The measurements of Fig. 2 are shown as somewhat distorted in order more clearly to illustrate the two different positions of the upper.

By reason of this exact compensation a shoe made on a pair of these lasts will fit each of them equally well and tightly, and will thus derive its form, to a much greater degree than has ever before been possible, from careful lasting on the first last.

In addition to this careful compensation for the change in shape due to turning, it will be seen that my improved first last may be characterized by being enough broader than the corresponding second last to support the edges of a sole beyond the seam, which project beyond the first lasts now used. A turned shoe made on these lasts may thus, if desired, be first-lasted on a machine of the type known as a bed lasting machine, as with a welt, and thus the ad-

vantages of the upward smoothing action of the wipers of that machine may be secured on turns as on welts.

After the first lasting, stitching, and turning operations, a turned shoe is relasted on its second last. This operation is of great importance, as the shape of the finished shoe depends largely on the second last, and on the operation of relasting or inserting the second last. My novel process of performing this operation is designed with a view to securing a tighter fit on the second last than has heretofore been feasible, while at the same time permitting the relaster to exercise greater control of the operation than has been the case up to the present time.

In my above-referred to prior application No. 443,043, is illustrated a form of apparatus which may be utilized in carrying out this novel process. The work-engaging parts of that apparatus are shown in a diagrammatic way in Figs. 4 to 10 herein, illustrating one manner of performing my process of relasting shoes, and it will be understood that in details of actuating mechanism and construction of parts the apparatus may, if desired, be substantially in accordance with that described and claimed in my said prior application.

As explained in that application my improved apparatus is designed to engage the shoe in a manner to broaden or stretch the upper of a shoe while a last is being seated therein, thus facilitating the seating of the last and permitting the upper afterwards to contract by its own elasticity, aided as I prefer by the longitudinal pull of a shoe horn on the counter portion of the shoe, into extremely tight engagement with the last. I find it quite feasible to secure relasted shoes as tightly secured about the enclosed lasts as lasted welt shoes, a result greatly superior to any secured by prior methods of which I am aware.

A roll 30, rotatable under control of an operator, is arranged to co-operate with a shoe horn 32, to seat a shoe S on a last L supported on a last pin 34. The relation of these parts before the machine starts is shown in Fig. 4. When the machine starts the roll first moves upward into engagement with the shoe bottom, as shown in Fig. 5, and is then rotated in the direction of the arrow in that figure until the forepart of the shoe is seated on the last.

It will be observed that the roll at this time engages the shoe forwardly of the shank, as distinguished from prior relasting devices which engage the shoe at the shank or heel seat. This gives a pushing effect which results in a marked broadening of the upper, the advantage of which has previously been pointed out. The difference in the effects of these various ways of engaging a shoe can readily be demonstrated experi-

mentally by holding a shoe and manually pushing on it from the forepart, producing the desired broadening, and then grasping it at the shank or heel seat and pulling on it, which, it will be found, narrows the upper to a degree which is very noticeable, and which requires considerable force to overcome in seating a last in a shoe so held, and which allows the upper to broaden when released, thereby tending to loosen it on the last.

A further advantage of engaging the shoe at the forepart as shown in Fig. 5, is that the toe end of the sole is pulled downwardly, so that the toe of the last cannot catch on the channel lip as it passes over it.

The sole of a turned shoe is made of stock so much heavier than the upper that, if the last can once be brought to seated position with respect to the sole, it is relatively easy to stretch the upper into place. Accordingly I find it advantageous, in securing the tight lasting which is one object of my process, to urge the upper relatively forward with respect to the sole as the shoe and last are being relatively moved, by pounding it at the toe with wiping hammer blows, or otherwise. This stretches the upper forwardly on the last, and diminishes the resistance offered thereby to the forward thrust of the last. The upper is afterwards pulled back into place by the rearward pull of the shoe horn in relasting the counter portion of the shoe.

It is further helpful, in securing the desired result, to arrange the roll so that the effective direction of the pushing force may be varied, in order to keep it parallel to the axis of the forepart of the last, regardless of the swing of the last. As an illustrative arrangement for this purpose, the roll 30 is of variable diameter, and may be moved axially under the control of the operator, to bring portions of different diameter (and consequent different peripheral speeds) in engagement with opposite sides of the shoe, thus varying the resultant effective direction of the pushing force exerted by the roll.

In relasting shoes by previous methods, "overshot" toes, produced by pushing lasts too far into their shoes were very difficult to guard against, because of the imperfect control of the relasting operation. This difficulty is entirely obviated according to my novel process, by providing a surface (illustrated as the friction surface of roll 30) which can slip when a last reaches seated position in a shoe, so that it will not move beyond that position even if the operator does not succeed in stopping the rotation of the roll at exactly the right instant. As explained in detail in my above-identified prior application, the roll 30 is pressed against the shoe with a force which can be adjusted to vary the friction between the roll and the

shoe to the correct amount to produce this result.

At the conclusion of the operation illustrated in Fig. 5, roll 30 is left free to rotate idly, and the apparatus is operated to actuate horn 32 to relast the counter portion of the shoe, as shown in Figs. 6, 7 and 8. At the same time roll 30 moves back through the shank to the heel-seat, co-operating with the horn by progressively forcing the shoe bottom against the last, and at the same time operating to some extent to level the sole against the last. Before the actuating mechanism of the apparatus comes to rest, the roll returns to the shank, as shown in Fig. 9, and holds the shoe bottom clamped under heavy spring pressure against the last.

It is advantageous at this step of the re-lasting operation to secure the upper of the shoe about the enclosed last, by lacing or otherwise, as the pressure of the roll 30 against the shoe bottom aids materially in securing a tight fit. This may be accomplished by inserting the instep block B and then lacing or otherwise securing the shoe upper in place, or alternatively by performing the lacing or securing operation first and then forcing the instep block B into place. As this block has somewhat of a wedge-shaped form this further tightens the shoe. It is to be noted that in the reverse operation of withdrawing this block it is also advantageous to compress the shoe bottom against the last as shown in Fig. 9.

The final operation of the machine is to tilt the last pin 34 into the position shown in Fig. 10 to present the relasted shoe in a convenient position for removal and to lower 40 the roll 30 to its original position.

As explained above it is desirable with some kinds of shoes to vary the details of this process as illustrated in Figs. 12 to 18. As will be hereinafter explained, in so modifying my novel relasting process it may be further desirable to mount the shoe engaging roll in a manner to prevent bodily movement longitudinally of the shoe and to arrange the driving mechanism therefor so that the roll may be rotated in either direction under the control of an operator.

In relasting a shoe in this way a toe shoe horn or distorting member, shown in Fig. 11, comprising a horn portion 36 and a handle 38, may be used as shown in Figs. 12 and 13 to stretch the lining of the shoe during the relasting of the toe in a manner to prevent wrinkling. This will obviate or at least minimize the necessity for what is now a subsequent operation in smoothing and stretching the lining with a hand implement called a lining knife. The shoe is assembled on a last in the machine as shown in Fig. 12 with member 36 between the toe portion of the shoe and the toe of the last,

the roll 300 is brought upwardly against the shoe bottom and rotated in the direction of the arrow in Fig. 13, while member 36 is withdrawn by the operator. It will be evident that this operation will result in smoothly seating the toe portion of the shoe on the last as explained in connection with the description of Fig. 5 and that the use of the horn or distorting member 36 will help to pull the shoe on the last while at the same time distending the lining in such a manner as to lay it smoothly about the last.

In preventing "overshot" toes by operating according to the modification being described, I find it desirable to maintain roll 300, after the rotation has been stopped, clamped against the same place on the shoe bottom as shown in Figs. 14 and 15, while the horn 32 is operated to relast the counter portion of the shoe. By this arrangement the forward portion of the shoe is clamped tightly in position and any tendency of horn 32 to pull the shoe rearwardly far enough to result in an "overshot" toe is positively prevented.

In case it is desirable in operating on a given kind of shoe to avoid strain on the back seam, roll 300 may be arranged to engage the shoe bottom with sufficient friction so that when it is rotated in the direction shown in Fig. 13 the shoe will be pushed rearwardly on the last further than its final position. Thereafter, the counter portion of the shoe having been relasted as shown in Figs. 14 and 15, the direction of rotation of roll 300 is reversed as shown in Fig. 16 to draw the shoe forwardly on the last to its final position, taking up the slack provided to give additional clearance while relasting the counter portion of the shoe.

Thereafter the upper may be secured about the last by closing the fly of the upper by lacing or otherwise, as shown in Fig. 17, corresponding to Fig. 9, and the relasted shoe removed from the machine after being moved to the position shown in Fig. 18, corresponding to Fig. 10.

In Fig. 19 is shown a view corresponding to Fig. 13 of my above-referred to prior application No. 443,043, showing a modification of the actuating mechanism of the machine shown in that application to make it possible to operate the roll 300 as shown in Figs. 12 to 18. The parts shown in Fig. 19 which have identical functions with corresponding parts in Fig. 3 of the said prior application are indicated by the same reference characters. Thus shaft 46 is a support upon which are loosely mounted a series of bell crank levers 110, 224, and 126 for actuating various parts of the machine and reference character 100 indicates a pinion which acts through mechanism fully described in the said prior application for ro-

tating the roll 300. The pinion 100 is keyed to shaft 46 to rotate therewith. Likewise 68 indicates the main cam shaft of the machine on which are mounted cams 120, 5 226, and 210 operating as described in the said prior application.

It will be noted that a cam indicated at 128 in Fig. 13 of the said prior application has been replaced by a sleeve indicated in 10 Fig. 19 of the present application at 129. Thus, while bell crank lever 126 may be adjusted as explained in my prior application to vary the position of roll 300, it will not have the bodily movement longitudinally of 15 the shoe during the operation of the machine which in the former design was effected by cam 128.

It will be observed that the drive mechanism at the right of Fig. 19 has been modified 20 to permit rotation of pinion 100 (and therefore roll 300) in either direction under the control of the operator. A gear 47, loosely mounted on shaft 46, is driven from a worm drive 40 by suitable gears 42 and 44. 25 A bevel gear 48 is secured to the gear 47 to rotate therewith, and operates through an intermediate gear 50 to rotate a third bevel gear 52 in the opposite direction. Bevel gears 48 and 52 are loosely mounted with 30 respect to shaft 46 and means is provided for connecting either of them to rotate that shaft under the control of the operator. A clutch face is formed on the inner surface of each of the bevel gears 48 and 52 and a 35 clutch member 54, which is keyed to shaft 46, is arranged between them to be moved into engagement with either of them by means of an operator-controlled bell crank lever 56. By this modification of the mechanism 40 of the machine shown in my said prior application No. 443,043 the roll 300 can be rotated in either direction at the will of the operator by manipulation of lever 56.

In Fig. 20 is shown a preferred construction 45 of the above-referred to shoe-engaging roll comprising a cushion layer 146 enclosed in a rubber friction layer 144 in which are formed vacuum cups 142.

The shoes being relasted must necessarily 50 be in temper and in some cases the soles may be sufficiently wet to make it possible for the roll to slip sooner than is desired unless a heavy pressure is used. To obviate such possible slipping there may be provided, as 55 shown in Fig. 21, a suitable fabric, such as a canvas belt 302 passing about roll 300 and suitable idler rolls 304. The canvas has a greater tractive force on a wet surface than has rubber. A similar arrangement may be 60 used in case it is desired to protect the shoe bottoms against possible soiling from roll 300.

While particular applications of my invention have been illustrated and described 65 it is not the intention to limit its scope there-

by or otherwise than by the terms of the appended claims.

Having described my invention what I claim as new and desire to secure by Letters Patent of the United States is:—

1. That improvement in methods of relasting shoes which comprises partially inserting a last in a shoe, supporting the last and engaging the shoe in a manner to allow for slippage under excessive resistance without changing the point of engagement with the shoe, and then relatively moving the shoe and the last and simultaneously broadening the shoe upper to facilitate the seating of the last and continuing said relative movement until the seating of the last causes slippage to occur.

2. That improvement in methods of relasting shoes which comprises partially inserting a last in a shoe, and then pushing the toe portion of the shoe over the last by engagement with the tread face of the sole forwardly of the shank in a manner to permit slippage to occur when the shoe is seated on the last to avoid undue strain or injury of the shoe.

3. That improvement in methods of relasting shoes which comprises seating the toe portion of a shoe on a last, and then progressively forcing the shoe bottom against the last and longitudinally thereof while seating the counter portion on the last.

4. That method of relasting shoes which comprises seating the forepart of a shoe 100 upon a last and thereafter applying pressure progressively along the shank of the shoe to shape the shank.

5. That method of relasting turned shoes which comprises partially inserting a last in 105 a shoe, and then seating the toe portion of the shoe over the last while maintaining the toe of the last separated from the sole until after it has passed the channel lip and constantly maintaining engagement of the sole 110 with the last rearward of the toe.

6. A method of making turned shoes which comprises the steps of providing a second last and a first last wide enough to support the edges of the sole and related to the second last by being of the shape and size of the inside of a shoe which when turned will tightly fit both the forepart and heel portion of the second last, lasting and stitching a shoe on the first last in the manner of a welt shoe, removing the last, and relasting on the second last in a manner to shape the shoe thereover.

7. A method of making turned shoes which comprises the steps of providing a 125 second last and a first last which is related to the second last as if formed therefrom by removing material from the top of the forward portion and the bottom of the rear portion thereof and by adding material to 130

the sides of the second last adjacent to the bottom thereof to compensate for the thickness of the shoe materials, and determining the size and shape of a shoe relatively to its second last by lasting it on the said first last.

8. That improvement in methods of relasting shoes which comprises inserting a last in a shoe, and moving the sole of the shoe rearwardly of the last while urging the upper forward relatively to the last during the seating of the shoe on the last.

9. That improvement in methods of relasting shoes which comprises partially inserting a last in a shoe, moving the shoe and the last longitudinally relatively to one another, while twisting them relatively to one another to seat the forepart of the shoe on the last, and applying pressure to the rear part of the sole progressively lengthwise of the last to facilitate the seating of the rear part of the shoe.

10. That improvement in methods of relasting shoes which comprises pushing the toe portion of a shoe on a last by engagement with the tread face of the sole forwardly of the shank, and varying the effective direction of the pushing force to guide the shoe to seated position on the last.

11. That method of relasting shoes which comprises the steps of relatively moving a last and shoe to seat the toe of the last further in the shoe than its final position in order to provide extra clearance at the heel, then seating the counter-portion of the shoe on the heel end of the last, and finally relatively moving the last and shoe in a direction the reverse of the first movement in order to place the last in its final position.

12. That method of relasting shoes which comprises bringing a friction roll against a shoe and rotating it to push the shoe on a last further than its final seated position to provide clearance about the heel, then seating the counter portion of the shoe on the last while the forward portion is held by the roll, and finally reversing the rotation of the roll to draw the shoe forward on the last to final position.

13. That method of moving shoes relatively to lasts which comprises placing a fabric in engagement with a shoe, pressing said fabric thereagainst to produce a considerable friction, and moving the fabric while pressed against the shoe frictionally to move the shoe relatively to a last.

14. That method of assembling a shoe on a last which comprises compressing the bot-

tom of the shoe against the last, and inserting the instep block of the last while the shoe bottom is compressed against the last.

15. That method of relasting shoes which comprises smoothing the lining of a shoe simultaneously with the insertion of a last by placing a horn member between the toe of the last and the inside upper toe portion of the shoe to stretch and smooth the lining as the shoe is seated on the last.

16. A method of relasting shoes which comprises simultaneously pressing a shoe against a last and relasting the toe of the shoe, and progressively pressing the rear part of the shoe bottom against the last and longitudinally thereof while relasting the counter portion of the shoe to prevent displacement of the previously-relasted toe.

17. That step in a method of relasting shoes which comprises relasting the counter portion of a shoe while progressively pressing the rear part of the shoe bottom against the last and longitudinally thereof.

18. For use in the manufacture of turned shoes, wherein there is employed a second last shaped in accordance with the form to be imparted to a finished shoe, a first last which is related to said second last by having less material across the top of the forward portion and across the bottom of the rear portion in order to compensate for the thickness of the shoe materials.

19. For use in the manufacture of turned shoes, wherein there is employed a second last shaped in accordance with the form to be imparted to a finished shoe, a first last which is related to said second last by being enough broader to come out flush with the edges of the sole of a shoe lasted thereon, and enough thinner to compensate exactly for the change brought about by turning the shoe, so that the turned shoe will just fit the second last.

20. That method of making turned shoes which comprises the steps of providing a second last and a first last differing from the second last in the shape and size of cross-sections through its various parts by amounts exactly to compensate for changes caused by turning a shoe lasted upon said first last, and determining the size and shape of a shoe relatively to said second last by lasting it upon said first last.

In testimony whereof I have signed my name to this specification.

ARTHUR F. PYM.
